(57) **CLAIM**

The ornamental design for a “posterior lumbar interbody fusion device”, as shown and described.

DESCRIPTION

FIG. 1 is a front perspective view of a posterior lumbar interbody fusion device showing our new, original and ornamental design;

FIG. 2 is a top view;

FIG. 3 is a bottom view;

FIG. 4 is a front side view;

FIG. 5 is a rear side view;

FIG. 6 is a right side view; and,

FIG. 7 is a left side view thereof.

The broken lines indicate unclaimed features of the article and form no part of the claimed design.
